S. ORENSTEIN.
WARDROBE TRUNK.
FILED JUNE 25, 1920.

UNITED STATES PATENT OFFICE.

SAMUEL ORENSTEIN, OF NEWARK, NEW JERSEY.

WARDROBE TRUNK.

Application filed June 25, 1920. Serial No. 391,580.

To all whom it may concern:

Be it known that I, SAMUEL ORENSTEIN, a citizen of the United States, and a resident of Newark, county of Essex, and State 5 of New Jersey, have invented certain new and useful Improvements in Wardrobe Trunks, of which the following is a specification.

This invention relates to an improvement 10 in wardrobe trunks and is designed to provide a trunk in which a follower in the form of a board can be attached to the trunk and supported in a horizontal or approximately horizontal position so that it 15 can be used as a table, but the primary use for which it is adapted is as an ironing board, this board and the trunk also being adapted for use so that the board is within the trunk when the trunk is closed, being 20 adapted for use as a follower so that the clothing is held snugly on the hangers customarily used in such trunks.

The invention further consists in the use 25 of a bar which is extensible and which is adjustable within the trunk so as to hold the board used as a follower in order that the board can not retreat and permit the clothing to be disarranged, and when extended, this bar forms a leg which supports 30 the outer end of the board when it is used as an ironing board.

The invention further consists in details 35 of construction that will be more fully described hereinafter and finally embodied in the claims.

The invention is illustrated in the accompanying drawing, in which Figure 1 is a section of part of a wardrobe trunk with the board shown in position as a follower, 40 and also being shown, in dotted outlines, in the position it assumes as an ironing board or table. Figure 2 is a perspective view of the board and associated elements to hold it in position as a follower. Figures 3 and 45 4 are detail sections showing a manner of securing a rod, on which the board is suspended, in fixtures alongside the trunk to permit its easy removal, and the manner of locking it when in position. Figure 5 is a front view and Figure 6 an edge view of a 50 modified form of fixture to permit adjustment as to height of the ironing board.

I illustrate only so much of a trunk as is necessary to show the cooperation of the

parts, in the drawing the part 10 being the 55 part of a wardrobe trunk in which garments are suspended, usually on rails 11 at the upper part of each side of the trunk, on which the clothes hangers 12 are arranged so that the garments 13 can be suitably disposed.

The board 14 can be of any desired form and it is adapted for use either as a table or as an ironing board and is suspended, when within the trunk, on the rails 11 by 65 means of a bar 15 fixedly secured at one end of the board 14, usually by sleeves or eye 16, the ends 17 of the bar projecting beyond the edges of the board so that the ends 17 rest on the top of the rails 11 and the board 70 can be pressed back to act as a follower against the garments 13 and hold them snugly in position, so that when the trunk is only partially filled with clothing the clothing can be held snugly in position.

In order to hold the follower I provide a means which is preferably adjustable for holding the board in position. This means comprises brackets 18 which are arranged at the sides of the trunk at a proper point 80 below the rails 11, usually about half way down, and I also employ a bar 19 which acts as a pressure bar against the board 14 and has another function as a leg of the board when it is used as an ironing board, 85 which function will be described hereinafter.

The bar 19 is extensible, the form shown comprising two members 20 and 21 which are hinged or pivoted together, as at 22, so 90 that they swing in parallel planes and when assembled are short enough to pass between the brackets 18 and are adjustable along these brackets, the form of adjustment comprising openings 23 in the brackets, one end 95 of the bar having a hook 24 to enter the perforations 23 in one bracket, and a latch 25 with a finger-piece 26 by which it can be operated and slid backward, this latch 25 being usually a spring latch and enters the 100 openings 23 of the other bracket.

It will be readily seen that when the hook 24 is put in one side of the trunk at a point where the proper pressure will be applied to the board 14, the bar is swung so that the 105 latch 25 catches in an opening in the opposite bracket and the bar is held in place against accidental movement. This bar also

holds the board against vertical movement, which can be done by placing a U-shaped clip 27 in the under side of the board at a proper point so that the rod 15 rests on the rails. The clip 27 is in the path of the bar 19 when the bar is in position between the brackets 18.

When the board is to be used as a table or as an ironing board the bar 19 is extended by swinging it so that the members form a leg, shown in dotted outline to the left of Figure 1, and to hold them in line suitable means, such as a clip 28 on each side, can be used, and the hook 24 catches into a ring 29 at the end of the board, although any suitable means for fastening the end of the leg and the end of the board can be used. The inner end of the board is supported in fixtures 30, one on each side of the trunk at the proper height, the end 17 of the bar 15 fitting in these fixtures.

One form of fixture, shown in Figures 3 and 4, has an opening 31 of about the same diameter as the rod 15, with a restricted entrance 32, the rod being cut away, as at 33, to form slots which permit the entrance of the ends of the rod through these restricted openings in the fixtures, as shown in Figure 3, and then when the board is swung upward to its normal position, as shown in Figure 4, the slotted part not being in register with the restricted opening, the board can not be withdrawn until it is again swung downward to the position shown in Figure 3. This is a simple manner of making the inner end of the board easily attachable and detachable to and from the trunk. The brackets 30 are usually made of sheet metal and the part that engages the rod is off-set so as to provide room for the end of the bar beyond the slot 32 to be housed.

A modified form of fixture is shown in Figures 5 and 6, this fixture 34 having a series of openings 35 similar to that shown in Figures 3 and 4, so that the inner end of the board can be placed at various heights to suit the individual who is to use it, this being also adaptable for the cheaper types in which the outer end of the board, instead of setting on a leg formed by the bar 19, can be supported on any suitable piece of furniture or fitting in a room, such as a window sill or the like.

It will be evident that changes can be made in the details of construction and also in the assembling of the parts without departing from my invention.

I claim:

1. The combination of a wardrobe trunk having hanger supporting rails and bar supporting fixtures, with an ironing board having a transverse bar to suspend it from the rails so as to serve as a follower and to support it in said fixtures so that it can be used as an ironing board.

2. The combination of a wardrobe trunk having hanger supporting rails and bar supporting fixtures, with an ironing board having a transverse bar to suspend it from the rails so as to serve as a follower and to support it in said fixtures, and an extensible bar adapted for engagement with the suspended board to hold it in position as a follower, said bar when extended serving as a leg for the outer end of the board, the bar, the trunk and the board having coacting parts to permit such use.

3. The combination of a wardrobe trunk having hanger supporting rails for the suspension of clothing and having fixtures on opposite front edges, with a board adapted to be suspended so as to act as a follower for clothing in the trunk, means for holding the board in position as a follower, and means supporting the board in the fixtures so that it is usable as an ironing board.

4. The combination of a wardrobe trunk having supporting rails for the suspension of hangers, a board having a transverse rod at one end and projecting beyond the board so as to be suspended from the rails, the trunk having slotted fixtures in its side edges into which the ends of the rod can be seated for using the board as an ironing board.

5. The combination of a wardrobe trunk having supporting rails for the suspension of hangers, a board having a transverse rod at one end and projecting beyond the board so as to be suspended from the rails, the trunk having slotted fixtures in its side edges into which the ends of the rod can be seated for using the board as an ironing board, an extensible bar which when extended acts as a leg for the ironing board, the trunk having brackets in which the folded bar can be placed to hold the board in position as a follower when the board is suspended from the rails.

6. The combination of a wardrobe trunk having rails at the top of the sides and brackets at the sides below said rails, with an extensible bar which when folded engages said brackets and having means for engaging the brackets so as to adjust the bar thereon, and a board having a bar on one end so as to suspend the board from the rails and having a device on the opposite end to receive the extended bar which acts as a leg for the board so as to permit its use as an ironing board.

7. The combination of a wardrobe trunk having rails at the top of the sides and brackets at the sides, said brackets each having a series of perforations, with a board having a transverse rod at one end so that the board can be suspended from the rails, and a bar comprising two members pivoted together so as to swing in parallel planes and when folded being adapted to lie between

the brackets, said bar having on one end a hook and on the other end a latch to enter the perforations in the brackets.

8. The combination with a wardrobe trunk 5 having hanger supporting rails and supporting fixtures, of an ironing board having transverse means at one end to suspend it from the rails or to support it in the fixtures,

and means at the other end cooperating with the fixtures to support it in horizontal position when serving as an ironing board. 10

In testimony that I claim the foregoing, I have hereto set my hand, this 17th day of June, 1920.

SAMUEL ORENSTEIN.
